R.H.Davis.

By Attorney

UNITED STATES PATENT OFFICE.

RULON H. DAVIS, OF SALT LAKE CITY, UTAH.

CHILD'S VEHICLE.

Application filed March 6, 1924. Serial No. 697,323.

To all whom it may concern:

Be it known that I, RULON H. DAVIS, a citizen of the United States, residing at Salt Lake City, in the county of Salt Lake and 5 State of Utah, have invented certain new and useful Improvements in Children's Vehicles; and I do hereby declare the following to be a full, clear, and exact description of the invention, such as will enable others 10 skilled in the art to which it appertains to make and use the same.

This invention relates to wheeled toys, and more particularly to the wheeled toy forming the subject matter of my application, 15 filed December 4, 1923, Serial No. 678,460, and comprising a body of torpedo outline and planes slidably mounted on the body to permit them to be arranged within the body when it is desired that the toy have the appearance of an automobile or arranged in 20 projecting relation with respect to the body when it is desired that the toy have the appearance of an aeroplane. There is also shown in said application a plane structure 25 which is removably mounted upon the body.

The primary object of the present invention is the provision of a toy of the character set forth wherein the planes are connected to the body in a manner to permit them to be 30 folded against the sides thereof when not required for use, and having means adapted to support the planes when arranged in position for use.

With the above and other objects in view, 35 the invention consists in the construction, combination and arrangement of parts hereinafter fully described and claimed, and illustrated in the accompanying drawing, wherein:

40 Figure 1 is a view in front elevation of the body of the toy, the planes being shown in position for use,

45 Figure 2 is a view in side elevation of the hood and front portion of the body, the plane appearing in this view, being shown folded against the side of the hood,

50 Figure 3 is a sectional view taken on a plane extending longitudinally and centrally through one of the planes and through the adjacent portion of the hood, the plane being shown in raised position,

55 Figure 4 is a sectional view taken on a plane extending vertically through the hood and planes illustrating a modified form of the plane supporting braces, one of the

planes being shown in raised and the other in lowered position, and

Figure 5 is a detail sectional view taken on the plane indicated by the line 5—5 of Figure 4.

60 Referring to the drawing by reference numerals, 1 designates the hood, 2 the front portion of the body, and 3 the cockpit entrance of the toy. The body and hood may, as shown in the hereinbefore identified application, be of such configuration that the toy will be similar in appearance to an aeroplane when the planes 4 are in raised position, and similar in appearance to a racing automobile when the planes are in lowered 70 position. When in raised position, the planes 4 extend outwardly from the sides of the hood 1 and when lowered they lie against the sides of the hood. To permit them to be raised and lowered, the planes 4 are connected to the sides of the hood 1 by hinges 5. The planes 4 are supported in their raised position by struts 6 which are connected to the planes by pivots 7. The free ends of the struts 6 pass through openings 8 in sides of 80 the hood 1, and adjacent these ends the struts are provided with notches 9 adapted to receive the bottom walls of the openings 8 when the planes 4 are in raised position. These walls constitute abutments against 85 which the walls of the notches 9 rest when the struts 6 are in plane supporting position. The connection between the walls of the notches 9 and the abutments is such that the planes are held in raised position against any 90 accidental downward movement. The planes 4 are held against any accidental upward movement, when in raised position by their hinged ends which engage the sides of the hood 1 above the pintles of the hinges 5. 95 When it is desired to lower the planes 4, it is only necessary to raise the free ends of the struts 6 out of engagement with the abutments. After this has been done the planes 4 gravitate into their lowered position. 100 When it is desired to raise the planes 4 it is only necessary to exert an upward pull thereon, and when they reach their raised position, in which position their hinged ends will contact with the sides of the hood 1, the 105 notched portions 9 of the struts 6 engage the abutments.

110 In Figures 4 and 5, there is illustrated a modified form of the means for supporting the planes in raised position. This means

comprises struts 6^a which are pivotally connected as at 7^a to the planes 4 and which extend through the slots 8 in the sides of the hood 1, the inner ends 6^b of the struts 6^a being curved. To these curved ends of the struts 6^a are connected contractile springs 9^a which are also connected to the sides of the hood 1, the springs being adapted to hold the struts 6^a in position to support the planes 4 in raised position and are adapted to maintain the struts 6^a in position to secure the planes 4 in lowered position. The struts 6^a pass through the forked ends 10 of brackets 11, and to receive the connecting members 12 of the forks 10, which members constitute abutments, the struts 6^a are provided adjacent their outer or pivoted ends with recesses 13. When the planes 4 are in lowered position, the recesses 13 receive the abutments 12, and hold the planes against the sides of the hood 1 against any accidental outward movement. When the planes 4 are lowered, the springs 9^a are under tension. Owing thereto, the springs 9^a will, when the struts 6^a are moved out of locking connection with the abutments 12, move the planes 4 into their raised position. The formation of the curved ends 6^b of the struts 6^a provides shoulāer portions 14 which engage the abutments 12 in such a manner as to hold the planes 4 in raised position, and these shoulders 14 are held in contact with the abutments 12 against casual movement by the springs 9^a.

To further simulate the appearance of an automobile or aeroplane, the hood 1 is provided with a propeller 15 which is adapted to be rotated by the air when the toy is in motion, and an element 16 which resembles the filling nozzle and cap of the radiator of an automobile is mounted upon the upper side of the hood 1 adjacent the forward end thereof.

It should be understood that the drawing is merely illustrative and does not pretend to give exact proportions. Furthermore, the said drawing is illustrative of a preferred construction, it being my expectation that

various changes and modifications may be made without departing from the spirit and scope of my invention.

What is claimed is:—

1. A toy of the character set forth, including a body provided with openings and abutments adjacent thereto, planes hinged to the body, and struts extending from the planes and passing into the body through said openings and provided with notches to receive the abutments. 55

2. A toy of the character set forth, including a body provided with openings and abutments adjacent thereto, planes hinged to the body, struts extending from the planes and passing into the body through said openings and provided with notches to receive the abutments, and springs secured to the body and to the inner ends of the struts. 65

3. A toy of the character set forth, including a body provided with openings and abutments adjacent thereto, planes hinged to the body, and struts extending from the planes and passing into the body through said openings and provided with abutment receiving notches and abutment engaging shoulders. 70

4. A toy of the character set forth, including a body provided with openings and abutments adjacent thereto, planes hinged to the body, struts extending from the planes and passing into the body through said openings and provided with abutment receiving notches and abutment engaging shoulders, and springs secured to the body. 85

5. A toy of the character set forth, including a body provided at its sides with openings, planes hinged to and extending laterally from the sides of the body, struts pivoted to the planes and passing through the openings into the body, and means adapted to releasably support the struts in position to maintain the planes in laterally extended position with respect to the sides of the body. 90

In testimony whereof I affix my signature.
RULON H. DAVIS.
